HENRY L. COLES, OF HAMILTON, OHIO, ASSIGNOR TO GUARDIAN METALS COMPANY, OF HAMILTON, OHIO, A CORPORATION OF DELAWARE

SAFE AND VAULT MEMBER AND CONSTRUCTION

Application filed April 24, 1930. Serial No. 446,817.

This invention relates to improvements in composite structural units, and more particularly to improved torch, and drill resistant safe and vault members or plates.

Heretofore, it has been proposed to use plates for safes and vault constructions and the like, including drill and abrasion resistant core or sheath members of high melting point metals, such as tungsten, molybdenum, 10 uranium, vanadium and the like in combination with each other and with their respective carbides. These materials are structurally efficient, but due to the high cost of materials and the high manufacturing cost 15 it has not been possible to bring them into extended use. Such members were usually associated with a sheath or core of a highly conductive, relatively soft metal, such as copper and its alloys. The composite members 20 so formed afforded complete resistance from attack by an acetylene torch or ordinary burglar tools, but due to the high cost of preparation they have not been generally used.

It is an object of this invention to provide 25 an improved torch, and drill resistant structural member of ferrous base materials, and in particular the invention provides an improved ferrous base composite plate for safe 30 and vault constructions.

It is also an object of this invention to provide improved and novel core members or inserts for burglar-proof plate constructions.

Yet another object of the invention is the 35 provision of an improved method of forming burglar-proof safe and vault members.

These and other desirable objects and advantages of the present invention will be described in the accompanying specification 40 and illustrated in the drawings, certain preferred embodiments being shown by way of illustration only, for, since the underlying principles may be incorporated in other specific structures, it is not intended to be limited 45 to the ones here shown, except as such limitations are clearly imposed by the appended claims.

In the drawings, like numerals refer to 50 similar parts throughout the several views, in which

Fig. 1 is a horizontal section of an improved composite plate, in a mold;

Fig. 2 is a detail, partly in elevation and partly in section of a core member;

Fig. 3 is a view taken on line 3—3 of Fig. 51 1, and

Fig. 4 is a view similar to Fig. 1 showing an alternative form of slat arrangement.

In the practice of the present invention a core or slat member 10 is prepared from an improved ferrous alloy of the type set forth and claimed in my application Serial No. 438,232, and comprising 13-20% manganese, 3-18% chromium, 2-4% carbon, the remainder being substantially iron. Desirable 60 results may be obtained with compositions including 15-18% manganese, 7-15% chromium, 2.2-3% carbon and the remainder iron. These slat members are cast up in the usual manner, and are provided with inserts 70 11, comprising a mesh of malleable iron rods or wire of any suitable dimensions, depending upon the size of the structure. Such reinforced members have a high degree of resistance to torches, as well as to mechanical 75 cutting tools, such as drills and the like, and are markedly abrasion resistant.

The alloys used are characterized by a scratch hardness of the order of 7.5-9 on Mohs scale, and, due to the high percentage 80 of iron, are distinctly cheaper than similar tungsten base constructions, without the sacrifice of any mechanical or structural efficiency.

The members 10 are cast in the usual manner and may be prepared in gangs, as indicated in Figs. 1 and 3. In this type of construction, I secure improved results by casting the members en bloc, suitable connecting lugs or studs, 12, being formed between the 90 members, and being adapted to subserve the common functions of spacing members and connectors between slab sections. These members are preferably spaced about 6" apart, although it will be understood that any 95 desired distance may be maintained. The composite slat assemblies, designated generally by the numeral 13, are made up of slats, 10, so arranged as to provide overlapping between the several slats, thus preventing any 100

direct apertures, from one side to the other. These members are set in position in a suitable mould 14 and spaced apart a suitable distance, and a sheath 15 of heat resistant metal cast therearound.

In the case of a cast metal sheath, it is preferred to coat the core members with a nitrogen producing composition, as more fully set forth and claimed in my Patent No. 1,755,913, issued April 22, 1930. The use of this process permits the securing of integrally bonded composite members.

If desired, the composite plates may be lightened, without sacrifice of any useful function, by providing centrally disposed air chambers 16 in the body of the sheath material, 15. These chambers prevent the formation of pockets in the metal in case an oxygen lance or other like instrument is used, and thus precludes the burning through of the structure.

While the pockets have been shown as centrally disposed in the composite plate, it will be understood that they may be arranged in any desired manner. It is also to be understood that the members 10 may be formed or disposed at any desired angle with respect to the surface of the plate members.

As shown in Fig. 4 the invention comprehends the assembling of the slat structures at any desired angle to each other, and, in this figure two such sets are shown juxtaposed, but at substantially right angles to each other. This type of construction is particularly suitable for use in safe and vault members which are substantially square-sided.

While there has been disclosed a sheath of metal around the core members, it will, of course, be appreciated that efficient results, for certain constructions, may be obtained by setting up the core members in situ and casting concrete or other plastic embedments therearound. These embedments may be of any desired thickness and of any suitable compositions, such as concrete or cement, which may contain drill, abrasion and torch resistant materials, such as carbides of such materials as zirconium, vanadium, chromium, and the like.

The composite structures above described may be made in the manner indicated and assembled at any desired point, or they may be included in safe and vault constructions or other types of building constructions in which it is desired to incorporate the improved physical and mechanical properties of such members.

It will now be appreciated that there has been provided an improved composite plate and process of making the same, the novel structures being susceptible of many and varied uses, and more particularly adapted for use in safes and vault constructions where

resistance to burglar tools, torches and the like is of prime importance.

I claim as my invention:

1. A safe and vault member comprising a cast metal matrix of high heat conductivity in which is embedded a plurality of slabs of metallic material in substantial parallelism, said slabs being tool-resistant and being made up of a composition consisting of 13 to 20% manganese, 13 to 18% chromium, 2 to 4% carbon and the balance iron.

2. A safe and vault member comprising a cast metal matrix of high heat conductivity in which is embedded a plurality of slabs of metallic material in substantial parallelism, and as so arranged present a continuous surface, said slabs being tool-resistant and being made up of a composition consisting of 13 to 20% manganese, 13 to 18% chromium, 2 to 4% carbon and the balance iron.

HENRY L. COLES.
